UNITED STATES PATENT OFFICE.

EDWARD CAMPBELL McDOWELL, OF HAMILTON, ONTARIO, CANADA.

BRAKE-BEAM.

1,232,882.

Specification of Letters Patent. Patented Apr. 17, 1917.

Application filed June 15, 1916. Serial No. 103,825.

To all whom it may concern:

Be it known that I, EDWARD CAMPBELL McDOWELL, a citizen of the United States of America, residing at Hamilton, in the Province of Ontario, Dominion of Canada, have invented certain new and useful Improvements in Brake-Beams, of which the following is the specification.

This invention relates to improvements in 10 brake beams and particularly to those of the type having a compression member, a tensioning member and a strut between the same. The general object of the invention is to improve and simplify the construction 15 of the device and better adapt it to the functions required of it.

More specific objects are to reduce the 20 axial moments about the end of the beam to a minimum and to enable it to be absorbed as quickly as possible. A further object is to provide a construction which will permit the elements to be readily taken apart and put together and which will permit the bearing or wearing surfaces to be 25 readily hardened by any suitable process.

And a still further object is to provide an 30 improved form of connecting member between the compression and tensioning members which while transmitting thrust will reduce the turning moment to a minimum.

The invention consists essentially of the 35 improved construction herewith described in the copy of the specification and accompanying drawings.

35 In the drawing,

Figure 1 is a plan view, broken intermediate of its length and showing the improved brake beam assembled.

Fig. 2 is an enlarged fragmentary view of 40 the connection between the compression and tensioning members of the beam.

Fig. 3 is a sectional elevation of the fulcrum strut.

Fig. 4 is an end elevation, partly sectional, 45 of the member connecting the compression and tensioning members of the brake beam.

Like characters of reference refer to like parts in the several figures.

Referring to the drawing, A represents 50 the improved brake beam comprising the compression member 10 provided intermediate of its length with a notch 11 and having its ends gradually increasing as shown at 12 to form suitable shoulders 13 with the

trunnions 14 on which the brake heads are 55 mounted.

The compression member is operatively connected to the tensioning member 15 which is substantially V-shaped having its ends 16 upset to develop the full section of 60 the member, the said ends being bent or offset and designed to make threaded engagement with the nut 17.

The tensioning member 15 is secured to the compression member 10 by suitable 65 brackets 18 of angle shape having orifices 19 and 20 through the ends thereof arranged in substantially parallel relation, the first said orifice engaging the trunnion 14 while the latter engages the offset end of the ten- 70 sioning member.

The tensioning and compression members 15 and 10 are braced at the center by the strut 21, one end of which is formed with an orifice 22 engaging the member 15 intermediate of the length thereof, while the other end 23 is bifurcated and designed to be sprung into engagement with the compression member 10 to which it is secured by the rivet 24 engaging with the notch 11. 80

In assembling the brake beam the orifice 22 of the strut 21 is engaged with the tensioning member 15 and the bifurcated end 23 of the strut is sprung into engagement with the center portion of the compression member 10. The brackets 18 are then placed in position so that the orifice 19 engages with the trunnion 14 and the orifice 20 engages with the upset and offset ends 16 of the tensioning member 15, whereupon the nuts 17 85 are threaded on the said ends and tightened into position. The rivet 24 is now passed through the bifurcated end 23 of the strut 21 and engaged with the notch 11 in the compression member 10. This notch 11, it will 90 be observed, prevents displacement of the strut with respect to the compression member and also prevents turning of the compression member. 95

It will be appreciated that the curving of 100 the ends of the tensioning member serves to bring the intersection of the projected center of the primary direction of the tensioning member with the center of the compression member considerably inside the center of the 105 trunnion 14 through which the braking power of the beam is applied to the wheels.

The aforesaid upsetting of these curved

ends of the tensioning member also serves to increase, to a marked degree, the resistance against straightening out inside of the strength for which the beam would be designed.

It will also be noted the end of the tensioning member is increased in thickness and turned parallel to the compression member to which it is connected by the bracket 18. 10 This construction reduces the rotational tendency of the end of the beam to a minimum. The horizontal component of the pressure on the brake beam is transmitted effectively to the compression member by 15 means of the shoulder 13, which is tapered at 12 into the compression member.

The formation of the trunnions 14 integral with the compression member is not only an economical form of construction but 20 also one of great strength and simplicity. The brakes may be placed directly on the projecting ends of the trunnions.

What I claim as my invention is:

1. In a brake beam and in combination, 25 a compression member having integral bearing trunnions, a shoulder on the inner end of the trunnions, a tensioning member and connecting member engaging the trunnions and the tensioning member and a strut extending between the compression and tensioning members.

2. In a brake beam and in combination, a compression member having integral bearing trunnions, a shoulder on the inner end 35 of the trunnions, a tensioning member and a strut extending between the compression and tensioning members, the ends of the said tensioning member lying in a straight line, and means for spacing said ends from 40 the compression member.

3. In a brake beam and in combination, a compression member, a tensioning member having curved ends of increased thickness and threaded and having an angular bracket 45 member connecting the ends of the tensioning member with the compression member and a strut extending between the tensioning member and compression member.

4. In a brake beam and in combination, a 50 compression member round in cross section having a notch therein, a tensioning member and a strut embracing both the tensioning and the compression members and having means to engage the notch adapted to prevent 55 turning of the compression member.

5. A brake beam of the class described comprising a compression member provided with trunnions and having enlargements near the end thereof forming shoulders with the said trunnions, a V-shaped tensioning member having offset ends, means for spacing said ends from the compression member and holding said ends substantially parallel thereto and a strut operatively connecting the tensioning and compression members intermediate of the length thereof. 60

6. A brake beam of the class described comprising a compression member provided with trunnions and having enlargements near the ends thereof forming shoulders 70 with the trunnions, a V-shaped tensioning member having offset ends, brackets substantially angle shaped provided with orifices arranged in parallel relation designed to engage the trunnions and the ends of the 75 tensioning member, and means for securing the tensioning member to the brackets.

7. In a brake beam and in combination a compression member having bearing trunnions, a tensioning member having ends extending substantially parallel with the trunnions, a strut between said members and a connecting member embracing the trunnions and the ends of the tensioning member. 80

8. In a brake beam and in combination a compression member having bearing trunnions, a tensioning member having ends extending substantially parallel with the trunnions, a strut between said members and connecting members embracing the trunnions and the ends of the tensioning member, each connecting member being formed with two parallel boxes adapted to receive the trunnion and end of the tensioning member, said boxes being separated by an angular portion. 85

9. In a brake beam, a compression member having trunnions, a tensioning member having its ends extending parallel to the trunnions but spaced therefrom and terminating inwardly of the trunnions, a strut between said members, and connecting members between the trunnions and the ends of the tensioning member. 100

In witness whereof I have hereunto set my hand in the presence of two witnesses.

EDWARD CAMPBELL McDOWELL.
